US0D1098162S

(12) **United States Design Patent** (10) **Patent No.:** **US D1,098,162 S**
Farray et al. (45) **Date of Patent:** **** Oct. 14, 2025**

- (54) **DISPLAY SCREEN OR PORTION THEREOF WITH A GRAPHICAL USER INTERFACE**
- (71) Applicant: **FieldClock LLC**, East Wenatchee, WA (US)
- (72) Inventors: **Joshua Scott Farray**, Chicago, IL (US); **River Sage Place Russell**, Ward, CO (US)
- (73) Assignee: **FIELD CLOCK LLC**, East Wenatchee, WA (US)
- (**) Term: **15 Years**
- (21) Appl. No.: **29/943,144**
- (22) Filed: **May 20, 2024**

Related U.S. Application Data

- (62) Division of application No. 29/797,202, filed on Jun. 29, 2021, now Pat. No. Des. 1,040,818, which is a division of application No. 29/726,471, filed on Mar. 3, 2020, now Pat. No. Des. 926,790.

(57) **CLAIM**

The ornamental design for a display screen or a portion thereof with a graphical user interface as shown and described herein.

DESCRIPTION

The FIGURE is a front view of a display screen or a portion thereof with a graphical user interface of our new design. The dashed broken line perimeter in the drawing illustrates a display screen or portion thereof and forms no part of the claimed design. The remaining dashed broken lines in the drawing illustrate portions of the graphical user interface that form no part of the claimed design.
